Dec. 646

N. P. Richardson, of Portland, Me.
Letters Patent No. 646. Dated May 21, 1854.

The schedule referred to in these Letters Patent, & making part of the same.

To all persons to whom these presents shall come:

Be it known that I, Nathaniel Putnam Richardson, of Portland, in the County of Cumberland, and State of Maine, have invented or produced a new ornamental design for a cooking stove, and I do hereby declare that the same is described and represented in the following specification and the accompanying drawings, letters, figures, and references thereof.

Of the said drawings, Figure 1 denotes a perspective elevation of my design, and exhibits the side, front, and top of the stove, the latter not being included in the design it being formed as heretofore made.

Figure 2 is a vertical section of the side plate, the side hearth or shelf, and the doors situated directly above and below the said hearth or shelf.

Figure 3 is a transverse section of the side plate and the lower two of its doors.

In the said drawings, A, B represent the front doors of the fire place; C, the side door or the end door of it; E, an ash pit or oven door; F, the main oven door; G, the side hearth; H, the main hearth; I, J, K, the legs.

a. is the base plate; b. is the base forming part of the side & end plates; c. is the top plate; and d. is the side plate.

The ornamental character or design found in each of the above members, and such as I wish to include in my claim, with the exception of that of the top and base plates is represented by the drawings, and will be clearly comprehended by any stove pattern maker of ordinary skill.

The ornamental appearance of the stove entitles it to be considered what may be termed a Peruvian pattern, as the ornaments of the panels of the doors and the feet or legs of the stove approach very nearly in their form and appearance to such as are found on many South or Central American monuments

2

Des. 646

In their combination in each of the members, they differ from any such monumental ornaments.

I would remark that what I claim is the general ornamental design of the stove, as shown in the side and front plates including the legs, and as represented in the accompanying drawings, and particularly, I claim that of each of the oven doors, E and F; that of the panel M, that of each of the front doors A.B. and that of each leg I.

In testimony whereof, I have hereunto set my signature, this first day of April, A. D. 1854.

Witnesses:-
